US00D923601S

(12) **United States Design Patent** (10) **Patent No.:** **US D923,601 S**
(45) **Date of Patent:** **** Jun. 29, 2021**

(54) **WIRELESS EARPHONE**

- (71) Applicant: **LG Electronics Inc.**, Seoul (KR)
- (72) Inventors: **Sojin Kim**, Seoul (KR); **Dongsoon Kim**, Seoul (KR); **Byungsoo Oh**, Seoul (KR); **Seungyup Lee**, Seoul (KR)
- (73) Assignee: **LG ELECTRONICS INC.**, Seoul (KR)
- (**) Term: **15 Years**
- (21) Appl. No.: **35/508,471**
- (22) Filed: **Jul. 31, 2019**

(80) **Hague Agreement Data**

- Int. Filing Date: **Jul. 31, 2019**
- Int. Reg. No.: **DM/204238**
- Int. Reg. Date: **Jul. 31, 2019**
- Int. Reg. Pub. Date: **Jan. 31, 2020**

(30) **Foreign Application Priority Data**

- Jan. 31, 2019 (KR) 30-2019-0005016
- (51) **LOC (13) Cl.** **14-01**
- (52) **U.S. Cl.** **USPC** **D14/205**

(57) **CLAIM**

The ornamental design for a wireless earphone, as shown and described.

DESCRIPTION

1. Wireless earphone
  - 1.1 is a front perspective view of the wireless earphone;
  - 1.2 is a front view thereof;
  - 1.3 is a back view thereof;
  - 1.4 is a left view thereof;
  - 1.5 is a right view thereof;
  - 1.6 is a top view thereof;
  - 1.7 is a bottom view thereof;
  - 1.8 is a second perspective view thereof, shown in a condition of use; and
  - 1.9 is a third perspective view thereof, shown in a condition of use.
- The broken lines depicting ear tips in reproductions 1.8 and 1.9 represent environmental subject matter that forms no part of the claimed design.

1 Claim, 9 Drawing Sheets
